UNITED STATES PATENT OFFICE.

HERBERT G. MACKINNEY, OF PROVIDENCE, RHODE ISLAND.

DESIGN FOR A CHARM FOR WATCH-CHAINS, &c.

SPECIFICATION forming part of Design No. 13,157, dated August 8, 1882.

Application filed June 29, 1882. Term of patent 3½ years.

To all whom it may concern:

Be it known that I, HERBERT G. MACKINNEY, of the city and county of Providence, and State of Rhode Island, have invented and produced a new and original Design for an Ornament or Charm for Bracelets, Watch-Chains, and Other Articles of Jewelry, of which the following is a specification, reference being had to the accompanying drawing, forming part hereof.

The leading feature of said design consists of a miniature representation of the toy, commonly known as a "cup and ball," consisting of a cup mounted on a staff or handle with a ball loosely attached to the staff by a cord or chain, to be thrown in the air within the limits of the attachment and caught upon said cup, the whole adapted to be secured to a bracelet, watch-chain, or other article of jewelry to which its attachment may be appropriate.

In the accompanying drawings, C represents the cup, S the staff, and B the ball. c is the cord or chain, attached to the staff S at one end and at the other to the ball B.

My design may be varied by varying the proportions, either relatively or absolutely, of the different parts, and also by changing the style of ornamentation on the same, and yet remain practically the same design.

What I claim, and desire to secure by Letters Patent, is—

1. The design for an ornament or charm for bracelets, watch-chains, or other articles of jewelry to which it may be appropriate, herein shown, and consisting of a miniature representation of a cup and ball, as herein described.

2. The design for an ornament or charm for bracelets, watch-chains, or other articles of jewelry to which it may be appropriate, herein shown, and consisting of staff S, cup C, chain c, and ball B, combined to present the appearance of a miniature cup and ball, as herein shown and explained.

HERBERT G. MACKINNEY.
